UNITED STATES PATENT OFFICE.

GEORGE E. REID, OF CUYAHOGA FALLS, OHIO.

METAL SIDEWALK FORM.

Application filed August 24, 1925. Serial No. 52,024.

My invention relates to knockdown forms as used in the process of making concrete sidewalks and other concrete structures and has for its object to provide a structure which will be light in construction and yet durable, sectional and finally portable.

A further object of the invention is to construct a form which will be composed of the least number of parts possible and at the same time constructed so as to leave the device free from any loose parts which could become easily lost.

A further object of the invention is to construct the device out of sheet metal of the tubular type and by arranging the parts in such manner that an increase in speed with respect to the assembling and dismantling of the form is produced.

With the objects above indicated and other objects hereinafter explained, my invention consists in the construction and combination of elements described and claimed.

Referring to the drawings:

Figure 1 is a perspective view of the device shown in assembled position.

Figure 2 is a top plan view of the tubular longitudinal member showing the arrangement of the slots and the locking means.

Figure 3 is a view showing the arrangement of the slots and the joining portion looking at the inner face of the tubular member.

Figure 4 is a similar view but looking at the outer face of the tubular member.

Figure 5 is a bottom plan view of the tubular member.

Figure 6 is a front view showing the partition plate and locking means.

Figure 7, is an end view of the same.

Figure 8 is a view showing two abutting sections and the means for locking them in position.

Figure 9 is a front view of the reinforcing member which fits over the partition plate shown in Figure 6.

Figure 10 is an end view of the same.

In the drawings 1 and 2 indicate the longitudinal extending side pieces formed of a single piece of sheet metal bent to shape and welded on the under side as at 3 and 4. In the shaping of the side pieces it is important that the inner faces 5 and 6 of the longitudinal side pieces be positioned at right angles to the surface to be concreted and it is further desirable to make the lower face 7 and 8 of sufficient width to insure a solid

setting or footing. It is further desired to construct the side pieces so that the outer sides 9 and 10 are battered or sloping. This construction affords a very durable and strong form to tubular structure. In order to more lighten the form sections 11 have been cut into the under side thereof.

In the upper sides 12 and 13 of the longitudinal side pieces and spaced suitably apart are cut recesses 14 which extend substantially downward into both the outer and inner sides of the side pieces. Into these recesses are placed division plates 15, the outer ends of which are cut to fit snugly into the recesses 14. As a means for preventing the displacement of these divisional plates 15, pivotal T shaped handles 16 are secured to the outer ends thereof and adapted to fit also within the recesses 14 and to be extended into horizontal position resting upon the outer side 10 and locking said division plate thoroughly in place.

In order to assemble a number of these forms together an angle 17 is secured to the battered side of the side pieces and substantially at one end thereof. At the opposite end and on the same side and center, a Z shaped member 18 is provided, pivoted in the center and adapted to extend, when in horizontal position, over an angle similar to 17, secured to the section to be secured thereto. As a means of aligning the several sections, plates 19 and 20 are rigidly fastened to the inside of the longitudinal side pieces by means of rivets or bolts 21, a portion of said plate extending forwardly a sufficient distance to enter the adjoining section. The use of the two plates holds these sections in line and by clamping the Z member 18 over the angle 17 they are prevented from becoming separated or disengaged.

As a further means of bracing the form of a channel member 22 is provided, its width being the same as the distance between the inside of the longitudinal side pieces. To this channel 22 is riveted or bolted a piece of flat iron 23 for the entire length thereof. Upon the top surface of the channel 22 and at the outer ends thereof are provided handles 24 which serve as a means for lifting this member. The particular feature of this member is its bracing and reinforcing quality. After the division plates 15 are in position and locked the channel 22 is placed over the said division plate 15, the flat iron 23 resting against the side thereof and the ends

of the channel 22 engaging the inner sides 5 and 6 of the side pieces 1 and 2 on both sides of the division plates. From this description it will be noted that it is practically impossible to move one of the longitudinal side pieces without moving the other.

In assembling the form the longitudinal side pieces 1 and 2 are placed upon the ground parallel with one another. Next the 10 division plates 15 are inserted within the slots 14 and the T-shaped handles 16 extended into horizontal position thereby locking the plates securely. After the several plates 15 have been secured in position the channel iron 22 is then placed over each of these several plates. The width of the channel 22 being of substantially the same width as the distance between the inside of the longitudinal side pieces, insures a snug fit, 15 it being necessary to lightly force these channels into place.

Now if it is desired to secure several of these forms together each section of the 20 form may be built up separately and then joined together by placing the ends containing the plates 18 and 19 inside of the end of the adjoining section containing the angle 17 thereby maintaining these sections in alignment. To secure these sections against 25 becoming disengaged or separated it is merely necessary to rotate the Z member 18 until the end thereof extends over and engages the upstanding leg of the angle 17.

It will be readily seen from the foregoing 30 description that my device is free from all individual or separate pieces which is necessary to most of the forms now used. The chances of losing any of the parts is thereby obviated and the construction simplified.

Having thus described my invention what I claim is:

1. In a form for concrete sidewalks, the 35 combination of longitudinally extending side members formed from a single sheet of metal, having their outer faces inclined outward and downward, recesses provided in the

upper surface of said side members and extending downwardly a substantial distance into the side portions, partition plates adapted to reside within said recesses and means carried by the partition plates for locking said partition plates, in the recesses adapted to engage the inclined outer faces of the side members.

2. In a form for concrete sidewalks, the 40 combination of longitudinally extending side members, tubular in cross section, formed from a single sheet of metal, recesses provided in the upper surface of said side members and extending downwardly a substantial distance into the side portions, partition plates having their ends adapted to reside within the recesses and a pivoted member secured to the outer end of said partition plates adapted to be extended into horizontal position through said recesses and to lock the partition plates against displacement.

3. In a form for concrete sidewalks, the 45 combination of longitudinally extending side members, tubular in cross section, formed from a single sheet of metal, recesses provided in the upper surface of said side members, and extending downwardly a substantial distance into the side portions, partition plates having their ends adapted to reside within the recesses, a pivoted member secured to the outer end of said partition plates adapted to be extended into horizontal position through said recesses and to lock the partition plates against displacement, a 50 plate secured to one end of said tubular member and adapted to engage the end of an adjoining tubular member to retain said members in alignment and a rotatable member secured at one end of the tubular side 55 member and having a depending portion adapted to engage the upstanding leg of an angle secured to the adjoining side member, to prevent separation thereof.

In testimony whereof, I hereunto affix my 59 signature.

GEORGE E. REID.
